DESIGN FOR A LAMP BASE

Henry A. Perlmutter, New York, N. Y.

Application August 15, 1939, Serial No. 86,692

Term of patent 3½ years

To all whom it may concern:

Be it known that I, Henry A. Perlmutter, a citizen of the United States, residing in the city and county of New York and State of New York, have invented a new, original, and ornamental Design for a Lamp Base, of which the following is a specification, reference being had to the accompanying drawing, forming part thereof.

Fig. 1 is a top plan view of a lamp base showing my new design.

Fig. 2 is a side elevational view thereof.

I claim:

The ornamental design for a lamp base, as shown.

HENRY A. PERLMUTTER.
